UNITED STATES PATENT OFFICE.

HENRY CURRIER, OF ROSE HILL, IOWA; HARRY WYMORE ADMINISTRATOR OF SAID
HENRY CURRIER, DECEASED.

FISHING-TOOL.

1,364,254.

Specification of Letters Patent.

Patented Jan. 4, 1921.

Application filed December 11, 1919. Serial No. 344,040.

To all whom it may concern:

Be it known that I, HENRY CURRIER, a citizen of the United States, and a resident of Rose Hill, in the county of Babaska and

5 State of Iowa, have invented certain new and useful Improvements in Fishing-Tools, of which the following is a specification.

10 My invention relates to grapples and has reference more particularly to tools for fishing dull bits and other implements from wells.

15 An object of the present invention is to provide an improved device of the character which, upon being lowered into a well or other boring, is adapted to engage and hold the object whereby the same may be removed.

20 Another object is to so arrange the grapping tongs and the jaws thereof that a variety of different objects may be readily removed from a boring.

25 With these and other objects in view the invention consists in certain novel features of construction and arrangement of parts as will be hereinafter set forth and pointed out in the claims, reference being had to the accompanying drawing, in which—

Figure 1 is a front elevation showing one form of my invention as in use;

30 Fig. 2 is an elevation of the device with the front or face plate removed;

Fig. 3 is a side elevation of the device;

Fig. 4 is a vertical section taken as on line 4—4 of Fig. 1;

35 Fig. 5 is a front elevation of a modified form of the device as in use;

Fig. 6 is a similar view enlarged and showing the gripping levers set for action;

Fig. 7 is a side view of the modified form; 40 and

Fig. 8 is a vertical longitudinal section of the same.

Fig. 9 is a vertical longitudinal section taken on a line 9—9 of Fig. 7.

45 Referring in detail to the drawings and more particularly to Figs. 1, 2, 3, and 4 it will be noted that I provide a body or stock portion comprising a face plate A and a back plate B spaced apart at the upper end

50 by a spacer block C through which the bolts D pass, these bolts also passing through the face and back plates and through the stock hanger straps E E provided with the elongated slots e at their upper ends; nuts d

are screwed on the ends of the bolts D and 55 against the said straps, thus securing the face and back plates and the hanger straps E E together.

Between the face and back plates a pair of levers F are disposed with their lower ends 60 G projecting below said face and back plates, said levers having the overlapped ears H with central perforations I through which the fulcrum member J passes, said fulcrum being a bolt which also passes 65 through the elongated slots a and b in the face and back plates, respectively.

The upper ends of the levers are pivotally secured to one end of links K, the other ends of said links extending on opposite 70 sides of the clevis L in overlapped relation and between said clevis and the slotted hanger straps E E and there held by the bolt M and the nut m.

The crossing portions or ears H of the 75 levers are cut out or recessed one-half their thickness so that the space between the face and back plates is the same as the thickness of the upper arms F of the levers.

The lower ends of the face and back 80 plates are provided with integral semi-circular flanges A' and B' to the lower face of which are held semi-circular extensions A² and B² by means of bolts A³ and B³ extending from the flanges A' and B' through 85 the open ended slots A⁴ and B⁴ in said extensions. These extensions may be moved outwardly and held to accommodate the tool to the diameter of the boring in which the tool is working. 90

The lower ends of the levers are provided with parallel obliquely set ribs N or knurls on their opposite faces and to such faces are pivotally secured the curved jaws O O having corresponding parallel ribs or knurls by 95 which the jaws can be adjusted to practically any angular position and held thereby by the bolts P passing through the lower ends of the levers and the said jaws.

The opposite side edges of the face and 100 back plates near their upper ends are provided with the triangular shaped notches Q and Q¹ into which project rigid studs or pins Q² and Q³ from the opposite faces of the upper arms F of the levers and in which 105 notches the studs or pins have lateral play, their inward movement being controlled and limited by stops which consist of a flat

plate Q⁴ having open end elongated slots Q⁵ therethrough and which are slidably and rotatably mounted on bolts against the front of the face plate adjacent the aforesaid 5 notches which are reentrant. By moving these stops inwardly or outwardly or swinging them on their pivot the throw of the levers can be controlled and hence the extent of the opening of the jaws at the lower 10 ends also controlled.

A cable or rod is secured to the upper end of the clevis L and by this cable the tool is lowered into the boring with the jaws G spread apart as in the position shown in 15 Fig. 2, the links K being horizontal and the bolt connecting them, the clevis and the hanger straps, lying within the extreme lower end of the elongated slots of the said hanger straps. When the lower end of the 20 stock comes in contact with the bit or article to be fished from the boring, the cable is given an upward jerk or pull whereupon the clevis is pulled upward carrying the bolt M up to the upper end of the elongated 25 slots causing the links to draw inwardly the upper ends of the levers and closing the jaws on the article and grip it between them where it is gripped and held by the serrated or sharp ends of the gripping jaws. The 30 bit and this tool can now be lifted out of the boring.

The device just described can be used in a plain boring, or it may be used in a well casing, as indicated in Fig. 1.

In Figs. 5, 6, 7 and 8 a modified form is shown and which comprises a stock or body portion consisting of a plate R having at its lower end an integral horizontal flange r, a reduced portion r' at its upper end in 40 which reduced portion an elongated slot r² is made and also provided at its central portion with an elongated slot r³.

Adjacent the lower end of the stock a pair of cross levers S S' are pivotally mounted and held by a headed bolt T which passes through a bulge or enlargement s' on the lever S' the head of the bolt being seated in the countersunk or depression s² in 45 said bulge thence through lever S and stock R and the nut s³ on the bolt binding against the stock and resting on the flange r by which it is prevented from turning off, thus constituting a nut lock.

The levers S and S' where they cross are recessed or cut out so that they present a uniform thickness throughout their length.

The upper ends of the levers S and S' are recessed or cut out on opposite sides s⁴ s⁴ and in these recesses are pivotally mounted 60 the lower ends of the toggle links U being secured to the upper ends of the levers in said recessed portions by bolts u and secured at their crossing to the reduced upper end of the stock by the bolt u' said bolt u' also serving as a means of securing the suspen-

sion means of the device, which consists of a plurality of strap sections V the adjacent ends overlapping and bolted together after the manner of a folding rule. The bolt u' passes through the elongated slot r² in the 70 upper end of the stock, and the lowermost section V' of the suspension means is slidably secured to the back face of the stock by the bolt u² which passes through the elongated slot in the central portion of the 75 stock, a washer u³ being placed on the bolt between the stock and the lower section of the folding suspension means; the slots r² and r³ are in vertical alinement and a washer u³ is also placed on the bolt u' between the stock and the said suspension section, all as plainly seen in Fig. 8.

The lower or jaw ends W of the levers are curved and are provided with gripping means which in the present instance consist 85 of hardened pointed screws X threaded through the jaws from the side edges in an oblique direction with the points projecting upwardly and inwardly through the inner edges of the jaws. These pointed screws, 90 which, it will be noticed, form teeth, can be adjusted to any degree desired so as to grip a large or a small article or tool which may have become broken or dropped into the bottom of the boring.

In using this form of device for fishing it is lowered into the boring or casing with the parts in the position shown in Fig. 6, the suspension device being folded out and extended to its full length. Upon reaching the 100 bottom or coming in contact with the tool or article to be fished, the suspending means is given a quick jerk upwardly which causes the crossed levers to close scissors-like, the bolts u¹ and u² rising to the upper ends of the 105 elongated slots r² and r³ and drawing the upper and lower ends of the crossed levers to swing toward each other and the pointed screws X to bite into and grip the article, as shown in Fig. 6. The entire device is then pulled upwardly from the boring or casing and the article released from the gripping jaws.

I claim:

1. A tool of the character described comprising a stock having a vertically sliding fulcrum, a pair of levers having overlapping ears mounted on said fulcrum, link members pivotally connected at one end to the upper ends of said levers, a lifting member, said link members having a vertically sliding connection with said lifting member, and independently adjustable stops mounted on one face of the stock for limiting the swinging movement of said levers.

2. A tool of the character described comprising a stock including spaced apart front and back plates, a vertically sliding fulcrum carried by said stock adjacent its lower end, a pair of levers having overlapped ears piv-

totally mounted on said fulcrum, link members pivotally connected at one end to the upper ends of said levers, a lifting member, said links having a vertically sliding connection with said lifting member, and adjustable stop means carried by one of said plates constituting the stock for limiting the swinging movement of the said levers.

3. A tool of the character described comprising a stock or body portion consisting of face and back plates spaced apart and carrying a fulcrum member, a pair of levers having overlapping ears mounted on said fulcrum between said plates, slotted hanger straps secured to said plates, link members pivotally connected at one end to the upper ends of said levers and at their opposite ends slidably connected with said hanger straps, entrant notches in the side edges of said face and back plates adjustable stops mounted on the face plate adjacent the notches, studs projecting from said levers within said notches, gripping jaws mounted at the lower

ends of said levers and a lifting clevis having a sliding connection with said hanger straps.

4. A tool of the character described comprising a stock consisting of face and back plates spaced apart and having a fulcrum member adjacent its lower end, a pair of levers having overlapping ears mounted on said fulcrum member between said plates, said plates having horizontal flanges at their lower ends, extension plates adjustably carried by said flanges, hanger straps secured to the upper ends of the face and back plates link members pivotally connected at one end to the upper ends of said levers and having a vertically slidable connection at their opposite ends with said hanger straps, a lifting clevis also connected with said links at their sliding connection, and adjustable gripping jaws carried at the lower ends of said levers.

HENRY CURRIER.

It is hereby certified that in Letters Patent No. 1,364,254, granted January 4, 1921, upon the application of Henry Currier, of Rose Hill, Iowa, for an improvement in "Fishing-Tools," an error appears in the printed specification requiring correction as follows: Page 1, line 4, for the words "county of Basbaka" read *county of Mahaska*; and that the said Letters Patent should be read with this correction therein that the same may conform to the record of the case in the Patent Office.

Signed and sealed this 26th day of April, A. D., 1921.

[SEAL.]

T. E. ROBERTSON,

Commissioner of Patents.
